FIG. 1.

FIG. 2.

FIG. 3.

FIG. 4.

INVENTOR

A. J. Charlton
BY Munro & Co.

ATTORNEYS

UNITED STATES PATENT OFFICE.

ALBERT JOHN CHARLTON, OF LOWDEN, IOWA

SUCTION MUFFLER.

Application filed June 10, 1920. Serial No. 387,923.

To all whom it may concern:

Be it known that I, ALBERT J. CHARLTON, a citizen of the United States, and a resident of Lowden, in the county of Cedar and State of Iowa, have invented a new and useful Improvement in Suction Mufflers, of which the following is a full, clear, and exact description.

My invention relates to improvements in mufflers for internal combustion engines, and it consists in the combinations, constructions and arrangements herein described and claimed.

An object of my invention is to provide a suction muffler that can be easily made from the types of mufflers already on the market, preferably from the Ford muffler type.

A further object of my invention is to provide a suction muffler having a plurality of mechanically rotated propeller blades, which when revolved, create a vacuum in the exhaust pipe, thus obviating back pressure.

A further object of my invention is to provide a suction muffler having a plurality of mechanically rotated propeller blades which tend to render the discharge more uniform, thus substantially diminishing the noise of the explosion.

Other objects and advantages will appear in the following specification, and the novel features of the invention will be particularly pointed out in the appended claims.

My invention is illustrated in the accompanying drawings, forming part of this application, in which—

Figure 1 is a side elevation of the suction muffler.

Figure 2 is a section through the muffler, Figure 3 is an enlarged vertical section through the muffler, taken on the line 3—3 of Figure 2,

Figure 4 is an end view, partly in section, of the muffler taken on the line 4—4 of Figure 2.

In carrying out my invention I provide a flat circular end portion 1, see Figure 2, which has two concentric grooves 2 and 3 on its inner face. An outwardly extended tubular portion 4, which is threaded on its outer surface, is integral with the end portion 1. The end of an exhaust pipe 5 is secured to the threaded tubular portion 4. An integral lug 6 extends inwardly from the end portion 1 and is directly opposite the tubular portion 4. The outer surface of the

lug 6 is substantially spherical in shape and has a socket 7 at its outer end which acts as a bearing for a reduced rounded portion of a square shaft 8. The tubular portion 4 has a passage-way 9 which extends from its outer end past the inner surface the end portion 1. A plurality of ducts 10 lead from the surface of the lug 6 to the passage-way 9. The external openings of the ducts 10 are at equal distance from the socket 7.

A flat circular end portion 11 also has two concentric grooves 12 and 13 on its inner surface. An outwardly extending tubular portion 14 is integral with the end portion 11. A central bore 15 through the tubular portion 14 acts as a bearing for the reduced circular portion 16 of the square shaft 8. A curved outwardly extending outlet pipe 17 is integral with the end portion 11. A passage-way 18, running through the center of the outlet pipe 17, has one of its openings disposed between the grooves 12 and 13 of the end portion 11. An oil cup 19 is provided to oil the bearing 15.

The square shaft 8 is provided with reduced portions 20 and 16 at opposite ends. The reduced portion 20 is journalled in the opening 7 of the lug 6. A washer 21 is disposed between the lug 6 and a shoulder 22 of the square shaft 8. A washer 23 is disposed between the inner surface of the end portion 11 and a shoulder 24 of the square shaft 8. The reduced portion 16 of the square shaft 8 is threaded at its extremity. A flexible driving shaft 25 is secured to the end of the reduced portion 16 by the nut 26. A passage-way 27 runs through the center of the square shaft 8 to the square shaft 8 of the reduced portion 20, where it terminates in an opening. An oil cup 28 provides oil to the passage-way 27, whereby the oiling of the bearing socket 7 of the lug 6 can be accomplished.

A plurality of propeller blades 29 are provided with centrally located square openings 30 which fit over the square shaft 8. Each propeller blade 29 has its square opening 30 turned at a different angle with respect to the side of the blade. Therefore, when the propeller blades are assembled, they will be turned at different angles with respect to each other, see Figure 3. A plurality of square spacing collars 31 adapted to keep the propeller blades 29 from longitudinal movement are provided upon the square shaft 8.

A cylindrical inner shell 32 is provided, having one of its circular ends disposed in the groove 2 of the end portion 1, and the other end disposed in the groove 13 of the 5 end portion 11. A concentric outer shell is also provided having one of its ends disposed in the groove 3 of the end portion 1, and the other end disposed in the groove 12 of the end portions 11. The inner shell has 10 an opening 34 at the end nearest the end portion 11.

The end portions 1 and 11 are provided with the lugs 35, 36 and 37 38 respectively. A rod 39 is disposed in the holes of the lugs 15 35 and 37, and a rod 40 is disposed in the holes of the lugs 36 and 38.

From the foregoing description of the various parts of the device, the operation thereof may be readily understood. The 20 flexible driving shaft 25 is rotated by any suitable means, preferably by a fan shaft on the engine which is not shown in the drawing. When the explosion has occurred in the cylinders of the engine, the expanded 25 gas rushes down the exhaust pipe 5, through the passage-way 9 and the ducts 10, where it enters the chamber 41. The revolving propeller blades create a vacuum which tends to obviate the back pressure usually 30 encountered in a muffler. Furthermore, the propeller blades tend to render the discharge of the products of combustion more uniform, instead of having a series of intermittent discharges at high pressure which

creates noise, the discharge is rendered 35 more uniform and at a lower pressure, thereby substantially diminishing the noise. It will thus be seen that the muffler accomplishes a double function to-wit that of reducing the back pressure and that of diminishing the noise. 40

I claim:

1. A muffler comprising a cylindrical casing, a shaft rotatably mounted in said casing, spaced apart fan blades carried 45 by said shaft, an inlet comprising a plurality of ducts disposed through one end of said casing, said ducts being positioned at an angle to said shaft whereby exhausted gases entering through said ducts are guided 50 toward the periphery of said blades, and a discharge pipe carried by said casing.

2. A muffler comprising a pair of concentric cylinders, a shaft rotatably disposed in the inner cylinder, a plurality of spaced 55 apart fan blades mounted on said shaft, said blades being staggered with respect to each other, an inlet comprising a plurality of ducts disposed through one end of the inner of said cylinders and concentric the 60 end of said shaft, said ducts being positioned at an angle to said shaft whereby exhausted gases entering through said ducts are guided toward the periphery of said 65 blades, and means provided for discharging the gaseous contents of said inner cylinder.

ALBERT JOHN CHARLTON.
